United States Patent Office

Des. 216,424
Patented Jan. 6, 1970

216,424

APARTMENT BUILDING

Moreau P. Estes, 1600 Hayes St. 37203, and Joseph Kott, Nashville, Tenn.; said Kott assignor to said Estes

Filed Dec. 9, 1968, Ser. No. 14,846

Term of patent 14 years

Int. Cl. D25—04

U.S. Cl. D13—1

FIG. 2

FIG. 3

In the drawings,

We claim:

The ornamental design for an apartment building, as shown.
